UNITED STATES PATENT OFFICE.

STEPHEN E. PARRISH, OF GRAND RAPIDS, MICHIGAN.

RIBBON-METER.

1,398,040.

Specification of Letters Patent.

Patented Nov. 22, 1921.

Application filed May 17, 1917. Serial No. 169,188.

To all whom it may concern:

Be it known that I, STEPHEN E. PARRISH, a citizen of the United States of America, residing at Grand Rapids, in the county of

5 Kent and State of Michigan, have invented certain new and useful Improvements in Ribbon-Meters; and I do hereby declare the following to be a full, clear, and exact description of the invention, such as will enable others skilled in the art to which it appertains to make and use the same.

This invention relates to a ribbon meter or measure particularly adapted for measuring the amount of ribbon or the like

15 wound upon a core, without the necessity of entirely unwinding the ribbon as has been usually done heretofore. This invention is particularly adapted for use in stores carrying large supplies of ribbon having, espe-

20 cial value for inventory. It is usual when an inventory of stock is made in a store carrying ribbon, to unwind, measure and re-wind each bolt of ribbon in order to determine the amount of the stock on hand. My

25 invention has for its primary object and purpose the provision of a ribbon meter in which the amount of ribbon in any bolt may be readily determined by the meter without unwinding the same; and the invention con-

30 sists in novel constructions and organizations of elements for effectively attaining this end together with many others not specifically enumerated but which will be apparent as understanding of the invention is 35 had from the disclosure of a preferred form thereof in the accompanying drawing in which:

Figure 1 is a substantially vertical section through the meter and,

40 Fig. 2 is an elevation thereof parts being broken away and shown in section to better disclose the construction.

Like reference characters refer to like parts in the views of the drawings.

45 In construction, a bottom plate of sheet metal 1 is provided from the edges of which sides 2 and 3 project substantially at right angles, the plate being relatively narrow at one end and then widening as shown, sides 50 2 and 3 similarly being bent as indicated at 4 and 5 in conformity with the shape of the plate 1. The ends of the plate 1 are similarly provided with end pieces 6 and 7 which project therefrom in the same direction as 55 the sides. In practice the bottom plate and

the sides 2, 3, 6 and 7 may be formed from a single piece of sheet metal though such particular formation from a single piece of sheet metal is not an essential feature of the invention. A cover plate 8 is provided of 60 the same form as the bottom plate 1, being connected thereto by screws 9 which pass through the cover plate and thread into turned lips 10 integral with the sides and ends heretofore noted. In this manner a 65 sheet metal housing is provided in which part of the mechanism of the meter is enclosed.

Within the housing a lever of modified channel form having a web and flanges 11 70 and 12 is pivotally mounted upon a pivot pin 13 which passes through and is disposed between the bottom and top of the housing. The flanges 11 and 12 incline toward each other and come together each side of the 75 pivot and at the upper end are connected to a member 14 which in turn passes through a slot in a cylindrical rod 15 slidably mounted in and passing through the sides 2 and 3 of the housing. A pin 16 passes through 80 the rod 15 and through a slot in the member 14 as shown. Normally one end of the rod 15 bears against a prong 17 which is fashioned at the end of a member 18 fixed to the side 2 of the housing, said prong 17 parallel- 85 ing the side 2.

The lever is spring actuated, one arm of a coil spring 19 bearing against the lever while the other bears against the inner face of the side 2 of the housing. The spring is 90 coiled around a pin 20 fixed to the bottom 1 and the tendency of the spring is to force the lever over until the end of the rod 15 bears against the prong 17 as described. A member 21 loosely connects to the lever and 95 passes through the side 3 of the housing at its end having a head 22 adapted to be engaged by the thumb of the operator whereby the force of the spring may be overcome and the lever moved in the opposite direction. The lower end 7 of the housing has a longitudinal slot 23 through which flanges 11 and 12 may pass. Flange 12 is turned at right angles, as indicated at 24, around the end 7 of the housing and then turned 100 back over the cover 8 of the housing as indicated at 25 and fashioned into an elongated loop 26 centrally and lengthwise of which a wire 27 is fixed. The loop 26 and wire 27 during movement of the lever are 110

adapted to pass over a series of indicating characters 28 which are placed upon the cover 8 as shown.

There is also placed upon the cover 8 a series of marks, indicated at 29, which are spaced a short distance apart each being indicated by a character, letters A to M inclusive indicating the marks in the disclosure made. A pointer 30 at one end is adapted 10 to associate with the series of marks 29, moving between stop pins 31 and being pivotally mounted at 32 adjacent the end 25 of the lever. A lower extension 33 is made to the pointer normally engaging with a projection 15 34 formed integral with the part 25 of the lever, whereby in normal position of the parts of the mechanism as shown in Fig. 2, the pointer is thrown over to its extreme position to the left. As soon as the lever and 20 attached rod 15 are moved away from normal position, a spring 35 associated with the pointer, has a tendency to move the pointer toward the right over the series of marks 29.

In the operation of measuring a bolt of 25 ribbon the first step is to take one thickness of ribbon and place it between the prong 17 and the end of the rod 15. In most cases the ribbon wound upon a core is wound with a strip of paper of equal length, and in such 30 case one thickness of ribbon and one thickness of the paper should be placed between prong 17 and the end of rod 15. This moves the lower end of the lever a short distance to the left and permits a slight movement of 35 the pointer to the right over marks 29, the extent of the movement being dependent upon the thickness of the ribbon and of the paper used with it. The pointer thereupon moves adjacent the end of one of the marks 40 29. For instance suppose it moves to the end of the line D. In such case line D of the indicating characters at 28 is the one to which reference must be made to determine the amount of goods in the bolt. After this 45 matter is determined the entire thickness of ribbon on one side of the core is inserted between the prong 17 and the end of the rod 15, whereupon the wire 27 moves a distance to the left and at its stopping point over the 50 selected line, such as D, of the scale indicated at 28, will be indicated the number of yards of ribbon in the bolt. The placing of the ribbon between the prong 17 and the end of rod 15 is accomplished by moving rod 15 55 away from the pointed prong by pressing on head 22, and then forcing the pointed prong 17 between the ribbon and the core on which it is wound, thereafter releasing the rod 15. The pointed prong readily inserts between 60 the ribbon and core. The scale at 28 is determined empirically and in actual practice the meter is capable of accurately measuring bolts of ribbons to within a very small fraction of the amount as determined by 65 unwinding and measuring the ribbon.

This meter is capable of measuring ribbons of all degrees of thickness without any necessity of a separate instrument for different kinds of ribbons. In the practical merchandising of ribbons, the cores on 70 which the ribbons are wound vary so little in size that they need not enter into the calculation at all. The thickness of the ribbon and the thickness of the entire amount of the ribbon on the core are the two determining 75 factors and both are recognized and taken care of in my invention.

Various changes in constructive detail may be resorted to without departing from my invention and accordingly I do not wish to 80 be limited to the specific disclosure made other than is necessitated by the terms of the claims which define the invention.

In this connection it is noted that the term ribbon used throughout the specification is 85 used in its generic sense and that the device is not only adapted to measure various thicknesses of ribbon but also any other similar wound goods such as cloth or the like which may be wound upon various types of cores. 90

I claim:—

1. In combination, a supporting structure, a pointed prong secured to and spaced a distance from said structure, a rod slidably mounted on the structure and yieldingly bearing against the prong, there being a series of lines of indicating characters carried by said structure, means connected to the rod and operable over the indicating characters whereby on insertion of the prong 95 under a thickness of ribbon wound on a core and engagement of the rod against the outer surface of the ribbon said means is carried to a point over the indicating characters indicative of the amount of material, and means controlled by the insertion of one thickness of ribbon between the prong and rod for determining the selection of the line of indicating characters to which the pointer 100 bears reference with respect to the ribbon, substantially as described.

2. In combination, a supporting structure, a pointed prong secured to and spaced a distance from said structure, a rod slidably mounted on the structure and yieldingly bearing against the prong, there being a series of indicating characters arranged in a plurality of lines and of indicating marks on the supporting structure, means on the supporting structure adapted to pass over 115 said marks and being made operable by the insertion of one thickness of ribbon to be measured between the prong and rod for the selection of the line of indicating characters to be used, and means connected to 120 the rod and operable over the lines of indicating characters whereby on insertion of the prong under a thickness of ribbon wound on a core and engagement of the rod against the outer surface of the ribbon, said 125 130

means is carried to a point over the selected line of indicating characters indicative of the amount of material on the core, substantially as described.

- 5 3. Means for measuring ribbon wound on cores comprising a supporting structure there being a series of lines of indicating characters for different thicknesses of ribbon carried thereon, a member movably 10 mounted on said structure and adapted to move over said characters, means operatively associated with said member for determining the line of characters to be used for a ribbon to be measured, and means for moving said member over the selected line a distance proportionate to the thickness of ribbon wound on the core, substantially as described.
4. In combination, a sheet metal housing, 20 a prong secured to a side thereof adjacent one end of the housing and spaced a distance from said side, a rod slidably mounted on the housing, a lever pivotally mounted between its ends within the housing and having connection at one end to said rod, means acting on the lever to force the rod against the prong, an elongated loop formed at the opposite end and bent back over the housing, said housing at its end being slotted to pass 25 the lever, a wire disposed between the ends of said loop, the housing being provided with a plurality of lines of indicating characters over which the loop and wire are adapted to pass, a pointer pivotally mounted 30 between its ends on the housing, and having one end engaged by said lever, spring means tending to move the other end of the pointer over the housing, the housing having a series of lines thereon relatively placed 35 according to different thicknesses of ribbon and with which said other end of the pointer is to register, and designated to correspond with said lines of indicating characters over 40 which said loop and wire are adapted to move, substantially as described.

5. In combination, a support, a prong se-

cured to a side thereof adjacent one end of the support and spaced a distance from said side of the support, a rod slidably mounted on the support, means yieldingly forcing the 50 rod against the prong, a lever pivotally mounted between its ends on the support and having connection at one end to said rod, the opposite end of the lever being movable over the support, a plurality of lines 55 of indicating characters on the support over which the free end of the lever is adapted to pass, a pointer pivotally mounted between its ends on the support and having one end engaged by the lever, and spring means 60 tending to move the pointer over the support, said support having a series of lines thereon with which said pointer is to register and designated to correspond with said lines of indicating characters over which said lever 65 is adapted to move, substantially as described.

6. In combination, a support, a prong secured in spaced apart relation from and to one side of the support, a rod slidably 70 mounted on the support, means movably mounted on the support, and connected to the rod, means for yieldingly holding the rod against the prong, said support having a plurality of lines of indicating characters 75 thereon over which said first mentioned means is adapted to pass, a pointer movably mounted on the support, and normally engaged by said means to hold it at a predetermined position, said support having a 80 series of indicating devices thereon with which said pointer is to register and designated to correspond with said lines of indicating characters over which said means is adapted to pass, and means for moving the 85 pointer over said indicating devices whenever freed for movement by a movement of said movably mounted means, substantially as described.

In testimony whereof I affix my signature. 90

STEPHEN E. PARRISH.
